UNITED STATES PATENT OFFICE

EDWARD A. HOFFMANN, OF READING, PENNSYLVANIA

APPARATUS FOR TRANSPORTING AND CONDITIONING READY-MIXED CONCRETE

Application filed July 13, 1931. Serial No. 550,467.

The present invention relates to improvements in apparatus for transporting ready mixed concrete from a central mixing plant to the points where construction operations 5 are being conducted. More specifically, the present invention relates to apparatus which is adapted to carry out the process described in my copending application Serial No. 262,789, and is a further improvement over the 10 apparatus disclosed in my copending application Serial No. 214,995.

The principal object of the invention is to provide an apparatus or more specifically a 15 rotatable tank for carrying out the conditioning process for concrete disclosed in my copending application Serial No. 262,789 which need not be raised at one end to discharge the so-treated concrete at the other or lower end. By so doing, I eliminate entirely the hoist 20 mechanism such as heretofore used as disclosed, for instance, in my copending application Serial No. 214,995.

Other objects of the present invention and 25 its resultant advantages will be apparent to those skilled in the art from the following specification and the drawings accompanying the same.

In the drawings,

Fig. 1 is an elevational side view of a motor 30 truck illustrating a preferred construction of a concrete conveying and conditioning tank made in accordance with the present invention mounted thereon, some of the standard and well-known constituent parts of the 35 truck and its operating mechanism being shown in more or less diagrammatic form.

Fig. 2 is an enlarged sectional view through the tank proper;

Fig. 3 is an end view of the same showing 40 the discharge opening;

Fig. 4 is a fragmentary sectional view through a wall section of the tank taken along the plane of line 4-4 in Fig. 2 showing the conditioning and moving means proper; and

45 Figs. 5, 6 and 7 are similar sectional views of modified forms of the conditioning and moving means.

Like characters of reference denote similar parts throughout the several views and 50 the following specification.

In Fig. 1 a truck is shown having a body-frame 10, a cab 11, an engine covered by a hood 12 and wheels 13 and 14. These parts are of the usual commercial design. Suitably mounted upon the frame 10 is a supplemental frame 15. The front end of supplemental frame 15 is extended upwardly at 16 to receive a trunnion 17 which is fastened to the center of the front part of a rotatable tank 18. The rear end of the tank is supported upon rollers 19. Near the front end of the tank 18 is an annular gear 20 which is in mesh with a pinion 21 which is mounted upon a shaft 22, engaging a sprocket gear 23, which by means of a chain 24 meshes another sprocket gear 25 mounted upon a shaft 26 which connects to the transmission of the truck and serves as a power take-off in the manner well known in the art. 27 is a clutch pedal in the cab which is connected by suitable leverage to a bar 28 which in turn is connected to an operating lever 29 fulcrumed preferably upon the supplemental frame 15 near the rear end of the tank 18. 30 is another operating lever having a common fulcrum with lever 29 which is connected by a bar 31 to an operating lever in the cab (not shown).

The tank 18 is rotatably mounted and it is obvious that the same may be rotated in either 35 a right or left direction with respect to the longitudinal axis of the tank, a clutch of any conventional form being in operative connection with the clutch pedal 27, so that the rotation in either direction may be accomplished by shifting of the levers at the rear 40 end of the tank or by the ones in the cab, in the manner well known in the art.

We now revert to the rotatable tank 18 the details of which are shown in Fig. 2. The tank is substantially cylindrical in shape, its rear end terminating conically at 32 defining a discharge opening 33. At a suitable point at the side of the tank is a filling opening covered by a closure 34 which is indicated 45 diagrammatically only being preferably of the construction shown in Patent No. 1,735,683 issued to me on November 12, 1929. Within the tank welded to the side walls thereof are preferably two blades 35. These blades 50

are spirally disposed within the tank and terminate at the outlet 33.

The cross section of a preferred form of the spirally disposed blade is shown in Fig. 4. The blade is pointed at its inner end and has a relatively broad base giving the blade a substantially triangular cross section.

36 is a circular plate provided with a hand wheel 37 adjustable upon a screw-threaded shaft 38 anchored within a spider at the outlet 33. This closure is also to be interpreted as diagrammatic only; any commercial tank closure may be used, the only requirement being that the closure must be water tight.

15 In the practicing of my process, I fill the tank about three-quarters full with premixed concrete through the filling opening at the side of the tank covered by closure 34. While this is being done, the outlet 33 is closed 20 tightly, of course. I then start the rotation of the tank 18 in the direction shown by an arrow in Fig. 4 marked "conditioning." At this time then, the wet, flowable concrete within the tank is subjected to a slow rolling 25 over motion which has the effect of releasing all air entrained within the concrete during the violent agitation to which it is subjected during the mixing of the raw materials. This also prevents stratification and setting of the 30 concrete and further subjects the concrete to a conditioning treatment which causes the expulsion of the entrained air in the concrete and thereby greatly improves its quality, this process being the same as set forth in my 35 copending application Serial No. 262,789. Attention is now particularly called to the angle of the blade 35 with respect to the cylindrical wall of the tank during the conditioning rotation. This blade is so disposed that 40 it will not rupture the surface of the concrete when thus rotated but slides through the surface without rupturing it and so does not violently agitate the mixture as is the case with the usual form and angle of agitating 45 blades of concrete mixers.

In order to discharge the tank after the destination is reached, the direction of rotation is reversed to correspond to that marked with an arrow in Fig. 4 and designated 50 "discharging." The outlet closure 36 is then gradually opened to a required degree when the blades 35 act as shovels, catch the concrete and force it out through the discharge opening.

55 While I have shown a preferred form of blade in Fig. 4, the cross sections of a blade shown in Figs. 5, 6 and 7 are equally as applicable to this process as long as they are so disposed within the tank that they will not 60 rupture the surface of the mixture nor agitate the mass when in the "conditioning" rotation and that they act as shovels as explained above when in "discharging" rotation.

65 The advantages of a concrete conditioner

as disclosed herein are obvious. The entire hoisting mechanism used heretofore to elevate the front end of the tank in order to discharge its contents, is entirely eliminated. The cost of a conditioning unit as shown in 70 the present invention is therefore greatly reduced.

I want it clearly understood that the invention is not to be limited to the specific construction illustrated in the drawings, 75 many modifications thereof falling within the scope of the appended claims being apparent to those skilled in the art.

What I claim as new, is:

1. Conditioning means for ready-mixed 80 concrete comprising a cylindrical tank having an outlet, means to rotate the tank in one direction for conditioning and a reverse direction for discharging, and blades spirally disposed along the inner wall of the said tank 85 extending to the said outlet at an obtuse angle with the said wall to prevent rupture of the surface of the concrete within the tank when rotated for conditioning and adapted to eject the concrete through the said outlet when rotated for discharging.

2. Conditioning means for ready-mixed 90 concrete comprising a cylindrical tank having a filling opening provided with a suitable closure in its cylindrical wall and an outlet 95 substantially in alignment with its longitudinal axis, means to rotate the tank in one direction for conditioning and a reverse direction for discharging, and blades spirally disposed along the inner wall of the said tank extending to the said outlet at an obtuse angle with the said wall to prevent rupture of the surface of the concrete within the tank when rotated for conditioning and adapted to eject 100 the concrete through the said outlet when rotated for discharging.

3. Conditioning means for ready-mixed 110 concrete comprising a cylindrical tank having a conical outlet, an adjustable closure to the said outlet, means to rotate the tank in one direction for conditioning and a reverse direction for discharging, and blades spirally disposed along the inner wall of the said tank 115 extending to the said outlet at an obtuse angle with the said wall to prevent rupture of the surface of the concrete within the tank when rotated for conditioning and adapted to eject the concrete through the said outlet when rotated for discharging.

4. Apparatus for transporting ready- 120 mixed concrete from a mixing plant to a place of usage comprising a vehicle, a cylindrical rotatable tank having an outlet mounted on the vehicle, means to rotate the tank in one direction for conditioning and a reverse direction for discharging, and blades spirally 125 disposed along the inner wall of the said tank extending to the said outlet at an obtuse angle with the said wall to prevent rupture of the surface of the concrete within the tank 130

when rotated for conditioning and adapted to eject the concrete through the said outlet when rotated for discharging.

5. Apparatus for transporting ready-mixed concrete from a mixing plant to a place of usage comprising a vehicle, a cylindrical tank mounted on the vehicle having a filling opening provided with a suitable closure in its cylindrical wall and an outlet substantially in alignment with its longitudinal axis, 10 means to rotate the tank in one direction for conditioning and a reverse direction for discharging, and blades spirally disposed along the inner wall of the said tank extending to the said outlet at an obtuse angle with the 15 said wall to prevent rupture of the surface of the concrete within the tank when rotated for conditioning and adapted to eject the concrete through the said outlet when rotated for discharging. 20 6. Apparatus for transporting ready-mixed concrete from a mixing plant to a place of usage comprising a vehicle, a cylindrical tank mounted on the vehicle having a conical outlet, an adjustable closure to the said outlet, means to rotate the tank in one direction for conditioning and a reverse direction for discharging, and blades spirally disposed along the inner wall of the said tank extending to the said outlet at an obtuse angle with the 25 said wall to prevent rupture of the surface of the concrete within the tank when rotated for conditioning and adapted to eject the concrete through the said outlet when rotated for 30 discharging. 35

7. Conditioning means for ready-mixed concrete comprising a cylindrical tank having an outlet, means to rotate the tank in one direction for conditioning the reverse direction for discharging, and continuous blades 40 spirally disposed immediately adjacent the inner wall of the said tank extending to the said outlet at an obtuse angle with the said wall adapted to be withdrawn from the concrete without agitating the same when the tank is rotated for conditioning and to eject the concrete through the said outlet when rotated for discharging. 45

8. Conditioning means for ready-mixed 50 concrete comprising a cylindrical tank having an outlet, means to rotate the tank in one direction for conditioning and a reverse direction for discharging, and blades spirally disposed along the inner wall of the said tank 55 extending to the said outlet, the said blades being of substantially oblique triangular cross section, having its base immediately adjacent the said wall, and its longer side 60 substantially at an obtuse angle with the said wall for the purpose specified.

9. Conditioning means for ready-mixed 65 concrete by means of a combined slow, rolling and flowing motion comprising a cylindrical tank having an outlet, means to rotate the

tank in one direction for conditioning and a reverse direction for discharging, and continuous blades spirally disposed along the inner wall of the said tank extending to the said outlet at an obtuse angle with the said 70 wall adapted to be withdrawn from the said concrete without interrupting its rolling and flowing motion when the tank is rotated for conditioning and to eject the concrete through the said outlet when rotated for discharging. 75

In testimony whereof I have hereunto set my hand.

EDWARD A. HOFFMANN.
